W. L. Hathaway, Dighton Mass:

Letters Patent No. 375. Dated May 27. 1851

The Schedule referred to in these Letters Patent and making part of the same

To all Persons to whom these Presents shall come:

Be it known

that I, W. L. Hathaway of Dighton in the County of Bristol
and State of Massachusetts, have produced a new and
original design for the front and side plates of a cooking
stove, and I do hereby declare that the said new design
is fully described and represented in the following speci-
fication and accompanying drawings, to which reference
is hereinafter made.

The figures of the accompanying plate
of drawings, represent my new design. Fig 1 is an
elevation of the side plate and Fig. 2 is a section of
the same, taken in the plane of the line A B fig 1. Fig 3,
is an elevation of the front plate.

Around the edge of the side plate are

the several mouldings a. b. c. Near the top of this plate is a panel formed by the mouldings e. f. g. h. Around the oven door, the fire chamber door and the panels i. k. are the mouldings l. m. n. o. Within these mouldings are the rays p. p. &c. cast in alto relief, forming a circle in the centre of each door and panels i. k. and running to the small circle q. q. which encloses an eight pointed star j. in the oven door and a six pointed star s. in the fire chamber door and the panels i. k. In the corners of these doors and the panels i. k. are the three leaves or parts of stars t. t.

Around the front plate are mouldings like those in the side plate a. b. c. The two larger and lower doors are ornamented with the mouldings l. m. n. o. the rays p. p. and stars j. j. &c. Those in the side plate. Around the two upper doors are the mouldings l. m. n. o. enclosing the panels t. t. within each of which are the eight pointed stars j. j.

Having thus described my new design I shall state my claim as follows

What I claim as my production and desire to have secured to me by Letters Patent, is the new design consisting of the several ornamental configurations and mouldings herein above described and represented in the drawings, for the side and front plates of a Cooking Stove.
